DESIGN.

—o—

A. L. HALLIDAY.

CARPET.

No. 17,767.

Patented Oct. 11, 1887.

UNITED STATES PATENT OFFICE.

ARTHUR L. HALLIDAY, OF NEW YORK, N. Y., ASSIGNOR TO THE BIGELOW CARPET COMPANY, OF CLINTON, MASSACHUSETTS.

DESIGN FOR A CARPET.

SPECIFICATION forming part of Design No. 17,767, dated October 11, 1887.

Application filed September 8, 1887. Serial No. 249,181. Term of patent 3½ years.

To all whom it may concern:

Be it known that I, ARTHUR L. HALLIDAY, of New York city, in the county and State of New York, have invented a new and original 5 Design for Carpets, of which the following is specification, reference being had to the accompanying photograph, which forms a part of the same.

The invention relates to a design to be worked 10 into or upon surfaces, such as carpets or similar fabrics; and it consists in the novel configuration and grouping of figures herein specifically shown and claimed.

The accompanying photograph is a face view 15 of a carpet showing my new design.

My design consists of a body portion, A, and a border, B.

The body portion A has a continuous main 20 stem light in character and curving back and forth with more or less regularity, bearing at intervals groups of flowers and leaves varying in size. From this main stem project long slender stems curving around in semicircular forms and supporting smaller leaves and clusters of small gem or star-shaped flowers, and in some places larger flowers and leaves. Around most of the curving branch stems are rows or groups of ornamental forms covered 25 with open-work, or of small skeleton flower forms. A few other small ornamental forms occur in the intervening spaces.

The border portion B has an inner margin ornamented with leaf forms and other small figures. The middle part of the border has a cluster of leaves and flowers, with larger flowers above and on each side of the center of the cluster. Long slender curving stems project from each side, bearing small leaves, some of them being supplemented with a row of ornamental forms covered with open work, as in 35 the body portion of the design. Alternating with these clusters or groups are smaller clusters of leaves and small flowers supported on a central stem having curved branches at the top bearing leaves and flowers. The outer 40 part of the border is ornamented with leaf and flower forms and scroll-shaped rows of ornamental forms covered with open work.

What I claim as new, and desire to secure by Letters Patent, is—

1. In a design for carpets, the body A, substantially as shown.
2. In a design for carpets, the border B, substantially as shown.
3. The design for carpets, consisting of the body A and the border B, substantially as shown.

ARTHUR L. HALLIDAY.
